Primary Examiner — Doris Clark(74) *Attorney, Agent, or Firm* — Michael Stanley Tomsa; Katten Muchin Rosenman LLP(57) **CLAIM**

The ornamental design for the ladder stabilizer, as shown and described.

DESCRIPTION

FIG. 1 is a front perspective view of a ladder stabilizer of the present invention;

FIG. 2 is a frontal view of the ladder stabilizer;

FIG. 3 is a rear view of the ladder stabilizer;

FIG. 4 is a first side view of the ladder stabilizer;

FIG. 5 is a second side view of the ladder stabilizer;

FIG. 6 is a bottom view of the ladder stabilizer; and,

FIG. 7 is a top view of the ladder stabilizer.

The broken lines shown in the views are for illustrative purposes only and form no part of the claimed design.
